UNITED STATES PATENT OFFICE.

CLINTON C. MURPHY, OF CHICAGO, ILLINOIS, ASSIGNOR TO P. H. MURPHY COMPANY, OF PARNASSUS, PENNSYLVANIA, A CORPORATION OF PENNSYLVANIA.

CAR-ROOF.

1,221,891.

Specification of Letters Patent. Patented Apr. 10, 1917.

Application filed October 1, 1914. Serial No. 864,372.

To all whom it may concern:

Be it known that I, CLINTON C. MURPHY, a citizen of the United States, and a resident of the city of Chicago, in the county 5 of Cook and State of Illinois, have invented a new and useful Improvement in Car-Roofs, of which the following is a specification.

This invention relates to metal car roofs, 10 composed of non-rigidly connected roof sheets, and has to do particularly with the fastening means for loosely securing the roof to the substructure.

Loose jointed roofs, as heretofore constructed, can adapt themselves readily to the changes in the relative positions of the several parts of the substructure due to the weaving, rocking, twisting, bowing and sagging of the car frame under severe usage 20 in service, but in the course of time the roof sheets may become shifted out of place, causing the joints to separate or to leak, and not infrequently the roof sheets tear loose from the fastenings.

25 The object of this invention is a metal car roof having all the advantages of a loose jointed roof and free from the foregoing disadvantages. Further objects of the invention appear in connection with the following description of the embodiment of the invention shown in the accompanying drawings.

In the drawings, in which like reference characters designate like parts in the several views, Figure 1, is a plan view of a 35 portion of a car showing the roof partly broken away to uncover the parts beneath;

Fig. 2 is a cross-section through the same on the line 2-2 in Fig. 1, drawn to a 40 slightly larger scale;

Fig. 3 is a side view of the same, drawn to the same scale as Fig. 2;

Fig. 4 is a large scale cross-section of the ridge construction, on the line 4-4 in 45 Fig. 1;

Fig. 5 is a large scale cross-section of the eaves construction, on the line 5-5 in Fig. 1;

Fig. 6 is a large scale cross-section of the 50 construction of the side seam or joint be-

tween adjacent roof sheets on the same side of the ridge, on the line 6-6 in Fig. 1;

Fig. 7 is a view similar to Fig. 6, showing another construction of the side seam;

Fig. 8 is a view similar to Fig. 4, showing another ridge construction;

Fig. 9 is a view similar to Fig. 5, showing the eaves construction modified whereby the angle clips are dispensed with;

Fig. 10 is a similar view showing another eaves construction; and

Fig. 11 is a fragmentary top plan view of the eaves construction shown in Fig. 10.

For purposes of illustration, the invention is shown in the drawings applied to a car 65 having wood side plates 11 and end plates 12, and wood side sheathing 13 and fascia boards 14. The roof substructure consists of carlines 15 and a ridge pole 16 supported thereby, and sheathing boards 17 extending 70 from ridge to eaves and supported at their ends on the ridge pole and the side plates. The invention may be applied to other forms of car construction than that shown in the drawings, and is applicable to steel 75 frame cars as well as to cars with frames made partly or wholly of wood.

As shown in the drawings, the roof sheathing boards are rabbeted to form a shallow groove running along the top of 80 the car adjacent to the eaves on each side, but these grooves may be omitted. Flashing strips 18, having their outer margins bent down over the eaves and secured to the side of the car, are arranged lengthwise of 85 the car in the shallow grooves. The inner margin of each flashing strip 18 is folded back over the main portion, forming a flat hook-shape flange 19. In the construction shown in Figs. 1, 2, 3, 5 and 9, the hook 90 flanges 19 are provided at intervals corresponding to the spacing of the roof sheets with upward projecting circular bosses 20. The side walls of the bosses 20 are slightly slanting. The roof sheets 21 extend from 95 the ridge to the eaves and are arranged in pairs, one on each side of the ridge, with inverted U-shaped flanges 22 at their ridge ends straddling the ridge pole and hooked together to form a ridge seam or joint. The 100

- eaves end of each roof sheet is folded under and back, forming a flat hook-shape flange 23, and at the middle of the eaves end of each sheet in an upward projecting circular boss 24, conforming to the shape of the bosses 20 in the flashing strips. The diameter of the bosses 24 is slightly greater than that of the bosses 20, whereby when the flanges 23 of the roof sheets are hooked into the flanges 19 of the flashing strips with the bosses 20 of the flashing strip within the bosses 24 of the roof sheets, there will be a slight space between the side walls of each pair of nested bosses.
- 15 In the construction shown in Figs. 1 to 6, inclusive, the side margins of the roof sheets are flanged up side by side with a slight space between them, and bent over to one side and down nearly to the body of one of the roof sheets. The extremity of the upper flange 25 is turned under the extremity of the lower flange 25^a thereby preventing the flanges from separating vertically, as shown in Fig. 6. In assembling the sheets upon the car the side flanges 25, 25^a, may be slipped lengthwise or telescoped one within the other, and the ridge flanges lapped together by dropping one inverted U-shaped flange 22 on the other after the sheets are in position.
- 30 The bosses 20 on the flashing strips may be nested together without affecting the side and ridge joints by lifting the eaves ends of the roof sheets, the flanges 19 and 23 being sufficiently flexible to enable this to be done.
- 35 The eaves ends of the side seams are covered by hood clips 26 which are bolted to the side of the car. Angle clips 27 bear upon the eaves ends of the roof sheets at the bosses 24 and hold them in engagement with the flashing strips. The hood caps and angle strips are provided with lugs 28 on their inner sides below the eaves angle. These lugs bear upon the flashing strip and space the horizontal under faces of the hood caps and angle strips above the flashing strip and roof sheets to prevent binding the latter, as shown in Fig. 5. The flashing strip 18 and undeturned eaves end flanges 23 may be so proportioned and arranged as to have sufficient stiffness to retain the bosses 20 on the flashing strip in engagement with the bosses 24 on the roof sheets, and the clips 27 may be omitted, as shown in Fig. 9.
- 40 The ridge corners of the roof sheets are secured by corner caps 29 which embrace the side and ridge seams and have base flanges 30 which rest on the roof sheets near their corners. Space is left within the corner caps around the side and ridge seams in order to
- 45 permit movement of the corners of the sheets upon the substructure. The corner caps are held in place by bolts 31 which pass through their centers and are secured to the ridge pole. The bolts 31 also secure the running

boards 33 are nailed or otherwise securely fastened.

50 In the construction shown in Fig. 7, the roof sheets have inturned inverted U-shaped flanges 34 along their side margins, the free edge of each of said flanges overhanging and terminating above the body portion of the roof sheet. The side margins of adjacent roof sheets are spaced apart, and supercarlines or mullions 35 are arranged crosswise 75 of the roof between the marginal flanges 34 of adjacent sheets, with a narrow space between each flange and the adjacent mullion. Seam covers 36 of inverted channel shape are supported on the mullions 35 with their side walls 37 inclosing the side flanges 34 of adjacent roof sheets. The extremity of each side wall 37 of the seam covers is doubled under and bent up into the space within the U-shaped flange 34 adjacent thereto; the intermediate part of the doubled-under portion 38 being in contact with the free edge of the U-shaped flange 34 and the free edge of the doubled-under portion 38 being in contact with the inner side of the outer wall of the U-shaped flange 34. This construction provides a flexible water-tight joint between adjacent roof sheets. The roof sheet flanges hold the seam covers in place upon the roof while permitting the seam covers to be readily removed and slipped in place endwise. The eaves ends of the seam covers 36 may be turned down and nailed or otherwise secured to the side of the car, or they may be covered and held in place by eaves hood clips similar to the hood clips 26.

55 In Fig. 8, a ridge seam construction is shown which permits of sidewise and endwise movement of the roof sheets, but which limits excessive movement crosswise of the car. The roof sheets have their ridge ends doubled over, and the outer part of each doubled portion is bent up into a double walled marginal flange 39. The inner extremity 40 of the doubled-over portion of the ridge end of the sheet lies above and is spaced slightly away from the body portion of the sheet inside its margin. Ridge caps 41 of inverted channel-shape are arranged lengthwise of the car at the ridge straddling the double-walled flanges 39 of each pair of oppositely arranged roof sheets. The side walls 42 of the ridge caps are provided with outturned flanges 43 along their bottoms, the extremities of the flanges 43 being doubled under and spaced below the intermediate portions thereof to form pockets or channels within which the extremities 40 of the flanges 39 of the roof sheets engage loosely. The width of the extremities 40 of the roof sheet flanges 39 is about the same as that of the pockets formed by the flanges 43 along the lower edges of the side walls of the ridge caps, and is considerably less than the width of the space between the side walls 130

of the ridge caps, thus permitting the roof sheets to move toward the ridge sufficiently to permit the disengagement of the flanges 40 and 43 in order to permit the ridge caps to be removed and replaced. The bosses at the eaves ends of the roof sheets normally prevent sufficient movement of the roof sheets toward the ridge to disengage the lateral flanges 40 from the pockets in the side walls of the seam caps. The disengagement of the eaves ends of the roof sheets from the flashing strips permits the roof sheets to be moved toward the ridge and thus permits disengagement of the ridge caps.

In the construction shown in Figs. 10 and 11, the eaves ends of the roof sheets and the hook-shape flanges of the flashing strips are not provided with bosses which fit into each other, but instead the flashing strips are provided with bosses 44 adjacent to the ends of the roof sheets near their middle points. The bosses 44 prevent endwise movement of the roof sheets in the direction toward the eaves, and thereby retain the hook-shape flanges 23 of the roof sheets in engagement with the hook-shape flange 19 of the flashing strip. The bosses 44 are convex on the side adjacent to the ends of the roof sheets, so that each roof sheet has a pivotal bearing against the adjacent boss and the roof sheets can swing about the bosses as centers in response to the weaving of the car frame.

It is evident that modifications in the forms of the several parts may be made, and the invention is not restricted to the precise forms shown in the drawings.

What I claim as my invention is as follows:

40 1. A car roof comprising roof sheets extending from ridge to eaves with the middle points of their eaves ends pivotally secured on top of the car near the eaves said roof sheets being independently movable along the ridge, and connected by loose joints.

2. A car roof comprising roof sheets arranged crosswise of the car and secured to the car for pivotal movement about their eaves ends said roof sheets being movable lengthwise of the car at the ridge, and loosely joined at their side edges.

55 3. A car roof comprising roof sheets extending from ridge to eaves and having their side margins connected by slidably joints, said sheets having a pivotal bearing on top of the car near the middle points of their eaves ends, the ridge ends of said roof sheets being provided with upstanding flanges, and ridge caps of inverted channel shape straddling the ridge flanges of sheets on opposite sides of the ridge and spaced therefrom to permit movement of the roof sheets lengthwise of the car and to limit crosswise movement thereof, said ridge caps permitting mutual crosswise movement of said

sheets and restraining their independent crosswise movement.

4. A car roof comprising roof sheets extending from ridge to eaves and having their side margins connected by seams providing 70 for relative endwise movement and with their ends pivotally secured on top of the car near the eaves, the ridge ends of said roof sheets being provided with upstanding inverted U-shape flanges, cover strips over 75 said flanges permitting sidewise movement thereof, said flanges and cover strips forming a floating ridge seam which responds to and mutually restrains the transverse movement of the roof sheets, and means for holding down said roof sheets at their eaves and ridge corners.

5. A car roof comprising roof sheets extending from ridge to eaves and having their side margins connected by seams providing 85 for relative endwise movement and with their ends secured on the car near the eaves against movement toward the eaves, the ridge ends of said roof sheets being provided with upstanding inturned horizontal 90 flanges, ridge caps having side margins with their lower edges turned in and hooked under said flanges for sidewise engagement and disengagement, and means for holding down said roof sheets and ridge caps. 95

6. A roof sheet having upstanding side and ridge flanges and a doubled under flange at the eaves end, and an upward projecting boss at the middle of the eaves and positioned over said doubled under flange. 100

7. A roof sheet for a car roof having means for pivotally securing the roof sheets at the eaves, said roof sheet having a double-walled upstanding flange along its ridge margin, the inner wall terminating in a lateral flange projecting away from the outer wall and with its free edge overlying and spaced from the body of the roof sheet whereby it is adapted to engage loosely with a ridge flashing strip. 105

8. In combination in a car roof, a roof sheet having a doubled under eaves flange and an upward projecting boss at the middle of the eaves end, and an eaves flashing strip having a doubled over inner margin hooked 115 into the end of the roof sheet and provided with an upward projecting boss fitting within the boss on the roof sheet.

9. In combination in a car roof, a roof sheet having a doubled under eaves flange 120 and an upward projecting boss at the middle of the eaves end, and an eaves flashing strip having a doubled over inner margin hooked into the end of the roof sheet and provided with an upward projecting boss 125 fitting within the boss on the roof sheet, and a clip secured to the car at the eaves and overlying the roof sheet adjacent to said boss.

10. In combination in a car roof, a roof 130

sheet having a doubled under eaves flange and an upward projecting boss at the middle of the eaves end, and an eaves flashing strip having a doubled over inner margin 5 hooked into the end of the roof sheet and provided with an upward projecting boss fitting within the boss on the roof sheet, and a clip secured to the car at the eaves and overlying the roof sheet adjacent to said 10 boss; said clip being spaced above said flashing away from the eaves and having a portion adapted to bear upon said flashing near the eaves.

11. In combination in a car roof, a roof

sheet having a circular boss at its eaves end, 15 an eaves flashing strip underlying said roof sheet at the eaves and having a circular boss fitting into the boss in said roof sheet, and a clip secured to the car outside the end of the roof sheet and having an inwardly extending portion overlying the roof sheet at the boss to hold it down upon the flashing.

Signed at Chicago, Illinois, this 28th day of September, 1914.
